DESIGN FOR AN ELECTRIC SANDING MACHINE OR THE LIKE

Stephen A. Crosby, Chicago, Ill., assignor to
Sterling Tool Products Company, a corpora-
tion of Illinois

Application September 29, 1943, Serial No. 111,233

Term of patent 14 years

(Cl. D37—1)

To all whom it may concern:

Be it known that I, Stephen A. Crosby, a citizen of the United States, residing at Chicago, in the county of Cook and State of Illinois, have invented a new, original, and ornamental Design for an Electric Sanding Machine or the like, of which the following is a specification, reference being had to the accompanying drawings, forming a part thereof, in which

Figure 1 is a side elevational view of an electric sanding machine or the like showing my new design; Figure 2, a top plan view thereof; and Figure 3, a front elevational view of the same.

I claim:

The ornamental design for an electric sanding machine or the like, as shown.

STEPHEN A. CROSBY.
